UNITED STATES PATENT OFFICE.

JOHN F. MEIGS AND SIGARD A. S. HAMMAR, OF SOUTH BETHLEHEM, PENNSYLVANIA,
ASSIGNORS TO BETHLEHEM STEEL COMPANY, OF SOUTH BETHLEHEM, PENNSYLVANIA,
A CORPORATION OF PENNSYLVANIA.

TRAINING AND FIRING MECHANISM FOR GUNS.

No. 927,260.

Specification of Letters Patent.

Patented July 6, 1909.

Application filed February 4, 1907. Serial No. 355,763.

To all whom it may concern:

Be it known that we, JOHN F. MEIGS and SIGARD A. S. HAMMAR, a citizen of the United States and a subject of the King of Sweden, respectively, residing at South Bethlehem, Northampton county, State of Pennsylvania, have invented certain new and useful Improvements in Training and Firing Mechanism for Guns, of which the following is a specification.

The object of this invention is to improve the means for sighting and firing guns, and to this end the invention consists in the combination with a sighting device and improved means for adjusting the gun, of improved electrical means for firing the gun at the instant when the proper adjustment is attained.

In the accompanying drawing means for imparting the vertical adjustment, or elevating the gun are shown, but it will be understood that the present invention relates equally to means for imparting a horizontal adjustment to, or training, the gun.

The invention will be described in connection with the accompanying drawing, in which,—

Figure 1 is a side elevation of part of a gun and its carriage, illustrating the present invention; Fig. 2 is a section on the line 2—2 of Fig. 1; Fig. 3 is an enlargement of part of Fig. 2; Fig. 4 is an enlarged section on the line 2—2 of Fig. 1; Fig. 5 is a section on the line 5—5 of Fig. 4; Fig. 6 is a perspective view of parts shown in Fig. 4; Fig. 7 is a section on the line 7 of Fig. 4; and Fig. 8 is a side elevation of the contact devices viewed from the line 8 of Fig. 4.

Referring to the drawing, 10 indicates the gun tube, 11 the sleeve which is provided with trunnions 12 mounted in a suitable carriage 13, 14 one of the recoil cylinders, and 15 a telescope or sighting device. These parts may be of any desired construction.

The elevating mechanism comprises a screw 15, the lower end of which cooperates with a swiveled nut 16 mounted in trunnions 17 in a bracket 18 on the carriage 13. The upper end of the screw 15 is mounted in a bracket or casting 19 which is hung upon a shaft 20, the shaft 20 being supported in a bearing in a bracket 21 connected with the sleeve 11. The screw 15 is turned by means of a gear 22 fast on the upper end of the

screw, and a gear 23 carried by the shaft 20. The shaft 20 is turned by means of two crank handles 24, 25, which handles are connected with wheels on the ends of the shaft.

Referring particularly to Figs. 3 and 4, 27, 28 indicate two insulated non-rotating conducting rings mounted in the bracket 21 concentric with the crank shaft 20. As shown in Fig. 7 these rings are electrically connected by insulated conductors 29, 30 with wires 31, 32 which are in circuit with the mechanism for detonating the primer of the gun and with a suitable source of electrical energy. This circuit is normally open between the rings 27, 28, and novel means for closing the circuit to effect the firing of the gun is provided as follows:

Referring particularly to Figs. 4, 5 and 6, the hand wheel or crank 33 which carries the handle 25, also carries a contact piece or pin 34 which is constantly pressed against the ring 27 by a spring 35. As the ring 27 is concentric with the shaft 20, it will be evident that the pin 34 travels on the ring 27 as the shaft 20 is rotated by the crank handles. A second contact piece or pin 36 is mounted in the axis of the handle 25 opposite the ring 28, the two contact pins being connected by a flexible conductor 37. The pin 36 is mounted in a slide 38 which is normally pushed away from the ring 28 by a spring 39. The normal break in the firing circuit is therefore between the contact pin 36 and the ring 28. Means are provided for closing the circuit by pressing the pin 36 against the ring 28 as follows: The slide 38 is arranged to move axially in a cylindrical shell 40. On the slide is fixed a ring 41 which is connected with the slide by spokes 42. The ring 41 rides on the outside of the shell 40, the spokes 42 extending through slots 43 in said shell. The spring 39 presses against a ring or shoulder 44 on the inside of the shell 40 and against a head 45 on the slide 38. The shell 40 is rigidly connected with the crank wheel 33 by suitable means, such as the screw 46, and it is provided with a slot 47 through which the conductor 37 passes. The handle 25 is swiveled on the shell 40 being held thereon by suitable means such as the pin 48 which enters an annular groove 49 in an extension 50, which is securely connected with the shell. Rigidly connected with the handle 25 is a bracket 51 upon

90

95

100

105

which is pivoted a trigger 52 having an arm 53, the extremity of which stands back of the ring 41.

Heretofore in mechanism for electrical firing of guns, the electrical connections have been more or less complicated and liable to become deranged. The electrical connections herein described are extremely simple in their character rendering failure in firing practically impossible. Only one contact is required to be made, and the operation of the movable element of the contact is positive. The ring 28 being concentric with the shaft 20 about which the handle 25 revolves, it will be evident that the contact pin 36 is always opposite a portion of the ring. The ring 41, which is connected with the contact piece or pin 36, rotates with respect to the handle 25, but the trigger arm 53 is always in position to engage some point of this ring to close the contact. One of the features of the invention essential to its simplicity and reliability is the placing of the contact pin or piece 36 in the axis of the handle 25, in combination with the ring 28.

It will be evident that certain changes in the mechanical details of the structure may be made without departing from the spirit and scope of the invention. Thus, it is obvious that the inner ring 27 and contact piece 34 may be reversed, the ring being placed on the crank wheel 33 and the contact piece on the fixed bracket 19, in which case the conductor 37 would be connected with the ring and the conductor 29 with the contact piece. The details of the means for connecting the handle 25 with the crank and for operating the contact piece 36 by the trigger may also be changed, but the preferred form is that illustrated and described.

The handles 24, 25, are arranged diametrically opposite to each other so that while the gunner is pulling on one handle he may be pushing on the other with the same effort, thus steadyng his body and permitting him to keep his eye constantly on the sight. In other words, the handles are arranged so that they move in opposite directions with respect to the gunner at the same time, that is, one of them coming toward him while the other is moving away. At the moment the gun is properly sighted it may be fired by pulling the trigger 52, while still grasping the handle 25. In case the object is moving, the gun may be fired while the gunner is moving the handles to follow the object.

It will be evident that the gearing, cranks, and firing mechanism herein described may be applied to drive any form of training mechanism as well as to the elevating screw illustrated, and the invention is, therefore, not limited simply to elevating mechanism.

Having described the invention what is claimed is:—

65 1. The combination with a gun and with

means for moving the gun comprising suitable gearing and a crank having a handle, of electric firing mechanism comprising a non-rotating conducting ring and a coöperating contact piece movably mounted on the crank and means on the crank for moving said contact piece into and out of engagement with said ring.

2. The combination with a gun and with means for moving the gun comprising suitable gearing and a crank having a handle, of electric firing mechanism comprising a non-rotating conducting ring independent of the crank and a coöperating contact piece movably mounted on the crank, said contact piece being coaxial with the handle.

3. The combination with a gun and with means for moving the gun comprising suitable gearing and a crank having a handle, of electric firing mechanism comprising a non-rotating conducting ring independent of the crank and a coöperating contact piece movably mounted on the crank, said contact piece being coaxial with the handle, and means on the handle for moving said contact piece into engagement with said ring to close the firing circuit.

4. The combination with a gun and with means for moving the gun comprising suitable gearing and a crank having a handle, of two non-rotating conducting rings, a contact piece arranged to travel on one of said rings, a second contact carried by the crank opposite the second ring and normally separated therefrom and means for moving said contact piece into engagement with said ring.

5. The combination with a gun and with means for moving the gun comprising suitable gearing and a crank having a handle, of two non-rotating conducting rings, a contact piece arranged to travel on one of said rings, and a second contact carried by the crank opposite the second ring and coaxial with the crank handle.

6. The combination with a gun and with means for moving the gun comprising suitable gearing and a crank having a rotatable handle, of two rings concentric with the axis of the crank, one of said rings being opposite the axis of the crank handle, a slide movably mounted in the handle, an insulated contact piece carried by said slide and normally separated from the corresponding contact ring, a trigger carried by the handle for closing said contact piece upon the ring, and a second contact piece normally in engagement with the other ring.

7. The combination with a gun and with means for moving the gun comprising suitable gearing and a crank having a rotatable handle, of two contact rings concentric with the crank, a contact piece normally in engagement with one of said rings, a slide carried by the crank and coaxial with the handle, a ring fixed on said slide, a trigger car-

130

ried by the handle and adapted to engage the said ring in any position of the handle, and a contact piece carried by the slide and adapted to coöperate with one of said contact rings when moved by the trigger.

8. The combination with a gun, a sighting device, and means for moving the gun comprising suitable gearing and two diametrically opposite handles arranged in proximity to the sighting device and connected with said gearing for moving the gun while sighting the same, of electrical firing means comprising two contact rings, and two contact pieces coöperating with said rings, one of said contact pieces being mounted coaxially in one of said handles.

9. The combination with a gun, a sighting device, and means for moving the gun comprising suitable gearing and two diametrically opposite handles arranged in proximity to the sighting device and connected with said gearing for moving the gun while sighting the same, of electrical firing means comprising two contact rings and two contact pieces coöperating with said rings, one of said contact pieces being mounted coaxially in one of said handles, the handle being rotatable with respect to said contact piece and provided with a trigger for closing the contact.

10. In an electrical firing device for guns, the combination with gearing for moving the gun, of a crank for turning said gearing, a shell rigidly connected to said crank, a handle rotatably mounted on said shell and pro-

vided with a trigger, a slide within the shell having a part constantly in the path of said trigger, a contact piece carried by said slide, and a relatively fixed ring coaxial with said contact piece and normally separated therefrom, said contact piece and ring being included in an electrical firing circuit.

11. The combination with a gun and with means for moving the gun comprising suitable gearing and a crank having a handle, of electric firing mechanism comprising a non-rotating conducting ring and a coöperating contact piece movably mounted on the crank, and means on the handle for moving said contact piece axially into engagement with said ring to close the firing circuit.

12. The combination with a gun and with means for moving the gun comprising suitable gearing and a crank having a handle, of two conducting rings which are stationary with respect to the crank, a contact piece arranged to travel on one of said rings, a second contact carried by the crank opposite the second ring and normally separated therefrom, and means carried by the crank handle for moving said second contact into engagement with the ring to close the firing circuit.

In testimony whereof we affix our signatures in presence of two witnesses.
